UNITED STATES PATENT OFFICE.

ALBERT A. WELLS, OF DETROIT, MICHIGAN.

AEROPLANE.

1,414,241.

Specification of Letters Patent. Patented Apr. 25, 1922.

Application filed August 9, 1920. Serial No. 402,104.

To all whom it may concern:

Be it known that I, ALBERT A. WELLS, a citizen of the United States, and a resident of Detroit, in the county of Wayne and State 5 of Michigan, have invented a new and Improved Aeroplane, of which the following is a full, clear, and exact description.

This invention relates to aeroplanes and has for an object the provision of means 10 whereby an aeroplane may be readily and simply adapted for flying in a vertical as well as in a horizontal direction.

Another object resides in the provision of means whereby a change in the direction of 15 flight may be simply and readily accomplished by a minimum number of controls and with the greatest degree of safety.

A further object of the invention comprises the provision of means whereby in 20 vertical flight head resistance is reduced as much as possible.

A further object resides in the provision of means whereby the speed and climbing ability of the aeroplane, while in flight, may 25 be changed.

A still further object resides in the provision of means whereby in changing from flight in a vertical direction to flight in a horizontal direction, or vice versa, the stability of the aeroplane may be at all times maintained.

Another object resides in the provision of the particular arrangement and construction of parts as will be hereinafter described and 35 claimed and are shown in the accompanying drawings.

The invention in general comprises an aeroplane having a fuselage of ordinary standard construction containing a source of 40 motive power therein. This aeroplane is provided with a front and a rear propeller both of which are movable under the control of the operator in a vertical plane, and the rear propeller in addition being movable in 45 a horizontal plane.

Provision is also made whereby the elevators of the aeroplane are simultaneously operated whenever the rear propeller is moved in a vertical plane, whereby they 50 may act as rudders to guide the aeroplane in its vertical flight.

The invention further comprises the ready and simple adjustment of the propellers whereby their adjustment to move the aeroplane either horizontally or vertically may 55 be uniform so that the stability of the aero-

plane is maintained at all times. Furthermore, the variation in the direction of thrust of the propellers with respect to the slope of the planes gives simple regulation, during flight, of the speed and climbing ability.

The invention further comprises the provision of a mechanical connection between a single motor and both propellers whereby power is efficiently transmitted thereto in 65 whatever position they may be in.

The invention further comprises the particular arrangement and construction of parts as are herein described and claimed and are shown in the accompanying drawings.

The invention is illustrated in the drawings, of which—

Figure 1 is a side elevation of the aeroplane showing in dotted lines a position of 75 the propeller for vertical flight;

Figure 2 is a partial plan view of the aeroplane;

Figure 3 is a longitudinal vertical section through the aeroplane; and

Figure 4 is a partial longitudinal horizontal section taken through the aeroplane.

As shown in the drawings, the invention comprises an aeroplane having a fuselage 1 within which a suitable source of motive power such as an engine 2 may be mounted. This engine is connected to a shaft 3 which is suitably journaled in standards of the fuselage, as shown at 4, 5 and 6. The aeroplane is provided with the usual supporting 85 wing portions 7 and 8 forming a wing panel. Ailerons 9 and 10 of the usual type are provided at opposite ends of the rear portions of wing portion 7. The aeroplane is provided at the front portion of the fuselage 1 with a propeller 11 which is rotatably mounted on a shaft 12 journaled in suitable ball bearings in a frame 13. This frame is pivoted on a stub shaft 14 journaled at its ends in standards 15 and 16 connected to the fuselage 1 in front of the engine 2. The inner end of the propeller shaft 12 is provided with a bevel gear 17 meshing with a similar bevel gear 18 on the stub shaft 14. The gear 18 in turn meshes with a bevel gear 19 rigidly connected to the front end of shaft 3 of the engine. This mechanical connection between the engine shaft and the propeller permits the propeller and its supporting frame 13 to be moved in a vertical plane from the horizontal position shown in Figures 1 and 3, to a vertical position, shown

in Figure 1, through a suitable slot or channel 20 formed in the nose of the fuselage 1.

At the rear of the aeroplane, and in line with shaft 3, is a rear propeller 21 mounted 5 on a shaft 22 which is suitably journaled in a rocking frame 23. This frame is pivotally connected to a rear portion 24 which in turn is pivotally connected to the rear of the body portion of the fuselage 1. The frame 23 is 10 pivoted to swing in a horizontal plane, whereas the propeller-supporting portion 24 is pivoted to swing in a vertical plane. The portion 24 is pivoted on the rear of the fuselage 1 on a stub shaft 25, shown more particularly in Figure 4. This stub shaft 25 is provided with a bevel gear 26 meshing on one side with a bevel gear 27 on a shaft 28 which connects by means of a universal joint 29 with the stub shaft 22 upon which 15 the propeller 21 is mounted. On the other side of bevel gear 26 a bevel gear 30 meshes and is attached to the rear end of shaft 3.

At the rear of the fuselage 1 the aeroplane is provided with the usual elevators 31 and 25 32. In the operator's position there are provided a plurality of controls whereby the movements of the aeroplane in different directions are directed by reason of the movement of the propellers, the ailerons and 30 the elevators in different directions. The frame 13 on which the front propeller 11 is mounted is moved in one direction or the other by means of cables 33 and 34 attached on opposite sides thereof and extending rearwardly over the pulleys 35 and 36 to a controlling drum 37. This drum is mounted on 35 a shaft which is supported in a frame 38 connected to the body portion of the fuselage. This shaft at one end is provided with 40 a controller wheel 39 having thereon a clutch portion 40 which is adapted to engage with a corresponding clutch portion 41 rigidly fastened to the drum 37. By moving the controller wheel 39 in one direction or the other the front propeller 11 while in motion 45 may be moved from the horizontal position shown in Figure 3 upwardly in a vertical plane. By means of cables 42 and 43, which are connected at one end to a drum 44 and at 50 the other end to arms 45 and 46 connected to the vertically pivoted portion 24, the rear propeller 21 may move in a vertical plane in either direction from the position shown in Figure 3. The drum 44 is mounted in a 55 rigid frame 47 and is adapted to be operated by a controller wheel 48, which is provided with a locking clutch mechanism similar to the one above described. The controlling cables 49 and 50 for each elevator are fastened to the cables 42 and 43 at a suitable 60 point so that whenever the rear propeller 21 is moved in a vertical plane, the elevators 31 and 32 are moved simultaneously in the same direction.

65 By reason of its mounting in the frame

portion 23, which is horizontally pivoted in the frame portion 24, the rear propeller 21 may also be moved around its pivot in a horizontal plane. This movement is effected by reason of the connection of cables 51 and 52 between rigid arms 53 and 54 on frame portion 23 at one end and to a foot-operated lever 55 situated at the operative position. These cables are guided by passing through guide posts 51' and 52' whereby 70 the propeller can always easily be rotated transversely irrespective of its vertical position. By moving this foot lever 55, the propeller 21 may be moved in a horizontal direction to the right or to the left, as shown in 75 Figure 4.

I have provided a simple unitary control means whereby ailerons may be moved in the usual manner either in the same direction simultaneously or in opposite directions. This mechanism comprises a hand lever 56 which, at its lower end, is connected to a pivoted yoke frame 57. This yoke frame in turn is adapted to be rigidly connected to a shaft 58 which, at its opposite 80 ends, is suitably journaled in supports from the floor 59 of the operator's position. At one end the shaft 58 is provided with a downwardly projecting end portion 60 adapted to carry a pulley 61 and a pulley 62. At the other end the shaft 58 is provided with an upwardly projecting end portion 63 carrying pulleys 64 and 65. The hand lever 56 may be moved in a vertical plane forward and backward and is provided with a latch member 66 adapted to engage with a ratchet 67 to hold the handle 56 in a particular position. The ratchet 67 and the yoke frame 57 are pivoted so that the hand lever 56 may likewise be moved 95 in a vertical plane transverse of the fuselage 1. In this movement the latch member 66 is adapted to engage ratchets 68, shown in Figure 4. Controlling cables, such as 69 and 70, extend from the hand lever 56 over 100 the pulleys 61, 62, 64 and 65 and are adapted to be connected to opposite ends of a rod 71 on each aileron. In a manner which is well known in the control of ailerons on aeroplanes, when the handle is moved directly forward or backward both ailerons are moved in the same direction and to the same degree, whereas if the handle 56 is moved to one side or the other one aileron is moved in one direction and the other aileron 115 is moved in the opposite direction in a manner well known in the art.

By reason of the provision of the various constructions and arrangements of parts above set forth, I have provided an aeroplane 120 in which movement in a horizontal and a vertical plane may be readily and simply effected. This plane can ascend in a much shorter distance where a flying start is taken, by reason of the fact that by ad- 130

justing both front and rear propellers to assist the planes in the vertical direction, a uniform vertical impulse is given the plane at both ends to a degree determined by the position of the propeller. It will also be noted that by changing the direction of the axial thrust of the propellers the angle between the thrust and the slope of the planes is changed, whereby the speed and climbing ability of the aeroplane is varied. By reason of the simultaneous movement of the elevators with the rear propeller they act as rudders assisting in the direction of the aeroplane for vertical flights. It will be noted that the surface of the ailerons bears a considerable proportion to the surface of the supporting wing 7, so that these ailerons are moved to the position shown in dotted line in Figure 1 and considerable reduction in head swing resistance is made and vertical flight is thereby improved. By providing for the separate control of the front and rear propellers, the fuselage can be kept in a horizontal line when flight is changing from the vertical to the horizontal direction. By moving the propeller 21, which is the rear propeller, further in the direction than that shown in dotted lines in Figure 1, a motion to the rear can be effected when the frame is ascending substantially vertically.

What I claim is:

1. An aeroplane comprising a fuselage having a single wing panel connected thereto, an internal combustion motor mounted in the fuselage slightly forward of the wing panel, a front propeller connected to the motor and normally disposed in line with

the shaft of the motor, a rear propeller connected to the motor and normally disposed in line with the shaft thereof, means for varying the inclination of the front propeller from normal position in a vertical plane upwardly, means for moving the axis of the rear propeller in two planes at right angles to each other, and a plurality of elevators attached to the rear of the fuselage, said last-mentioned means adapted to move said elevators with said rear propeller when the rear propeller is moved in one of the said planes.

2. An aeroplane comprising a fuselage, a wing panel connected thereto, an internal combustion motor disposed in the fuselage slightly forward of the wing panel, said fuselage having an operator's position rearwardly of the internal combustion motor, a driving propeller at the front of the fuselage connected to said motor, a propeller at the rear of the fuselage connected to said motor, the axes of both of said propellers normally being disposed in line with the plane of said motor, manual means in the operator's position for moving the axis of the front propeller upwardly from the normal position in a vertical plane, manual means in said position to move the rear propeller in a vertical plane, a plurality of elevators attached to the fuselage, said last-mentioned manual means adapted to move said elevators simultaneously with the movement in a vertical plane of the rear propeller, and pedal operated means for moving the axis of the rear propeller in a horizontal plane.

ALBERT A. WELLS.
